CORK PLUG

José Furquet, Buenos Aires, Argentina

Application July 27, 1939, Serial No. 286,936

5 Claims. (Cl. 215—48)

The present invention relates to stoppers for bottles or similar receptacles and particularly those containing gas evolving beverages such as champagne, cider and similar liquids.

5 An object of the invention resides in providing a composite stopper wherein the cork plug is adapted to engage the inner neck of the receptacle and a core member which is of more rigid material than the cork is arranged within the stopper so that the outer end of the stopper will be reinforced so as to prevent breakage thereof during removal of the stopper from the neck of the receptacle.

10 15 A further object of the invention resides in providing means within the cork plug for preventing deterioration of the reinforcing core member.

20 Other and further features and objects of the invention will be readily apparent from a consideration of the following description and the annexed drawing wherein an exemplary embodiment of the invention is disclosed.

In the drawing:

25 Fig. 1 is a longitudinal sectional view of the outer part of the stopper element showing the recess therein.

30 Fig. 2 is an elevational view of the cup-shaped member adapted to fit over the inner end of the core.

35 Fig. 3 is an elevational view of the core member.

40 Fig. 4 is a sectional view of the composite stopper illustrating the core member within the outer stopper element.

45 Fig. 5 is a similar sectional view showing the manner in which the outer stopper element is deformed after insertion in the neck of a bottle or receptacle.

50 As shown in Fig. 1 the outer element or member 1 of the stopper is preferably formed of cork and being generally cylindrical-shaped particularly on the outer peripheral surface thereof. The stopper element 1 is provided with a longitudinally extending recess 3 as illustrated in Fig. 1. The recess terminates within the outer stopper element so as to provide an end wall 2. In other words the recess 3 does not extend entirely through the outer stopper element. The recess is preferably cylindrical in shape and concentric with the axis of the stopper element 1.

55 A core member 4 is adapted to be arranged within the recess 3 and the shape of the core member therefore corresponds to the shape of the recess 3. The core member may be formed of any relatively rigid material such as wood.

It will be appreciated, however, that other materials may be employed in forming the core member 4. When the core member is formed of wood and particularly when the grain thereof extends longitudinally of the core member means 5 may be provided for covering the inner end of the core member. Such means may take the form of a cup-shaped member 1 which is adapted to fit over the end of the core member. The cup-shaped member 1 may be formed of any suitable 10 material which is impermeable to the gases evolved by the beverage in the bottle or receptacle. Thus, the cup-shaped member may be formed of a metal foil such as aluminum or paper treated to provide a gas-impermeable cover for 15 the inner end of the core member.

The core member 4 with the cup-shaped element 1 arranged on the end thereof is introduced through the recess 3 in a manner as illustrated in Fig. 3 so that the composite stopper is 20 thus provided with a relatively rigid core for reinforcing the outer end of the plug.

The end 2 of the cork element is adapted to be inserted within the neck of the bottle or receptacle and the outer cork element is thus deformed and assumes a shape somewhat like that represented in Fig. 5. The neck of the bottle or receptacle compresses the outer cork element to provide a relatively thin shell around the core member 4 as indicated at 5. That portion of 30 the outer cork element 1 which remains outside of the bottle neck is not compressed so as to form an enlarged head portion 6 as shown in Fig. 5. When it is desired to remove the composite stopper from the neck of the receptacle 35 lateral forces may be applied to the head portion 6 so as to wiggle the stopper preparatory to the removal thereof from the bottle neck. Such lateral pressure, however, will not cause the outer cork element to be broken along the 40 narrowest portion 5 since the core member 4 provides reinforcement for the outer end portion of the composite stopper. Thus, the composite stopper may be readily removed from the neck of the receptacle or bottle without breaking the 45 cork and without the use of a corkscrew or similar instrument.

While the invention has been described with reference to the particular shape of the recess 3 and the core member 4 and with reference to 50 specific types of materials it is apparent that changes may be made therein by those skilled in the art. Such modifications may be made without departing from the spirit and scope of the invention as set forth in the appended claims. 55

I claim:

1. A stopper for bottles, particularly those containing gas evolving beverages, consisting of, a cylindrical stopper element provided with a concentric cylindrical recess therein, a cylindrical core member fitted into said recess, a cup-like member fitted over the inner end of said core within the recess, and said cup-like member being impermeable to gases.
10. 2. A stopper as claimed in claim 1 wherein the cup-like member is made of metal foil.
3. A stopper as claimed in claim 1 wherein the cup-like member is made of gas-impermeable paper.
15. 4. A stopper for bottles adapted to contain a gas-evolving beverage comprising, a stopper ele-

ment having a cylindrical peripheral surface, said stopper element having a longitudinal recess therein, a core member fitting within said recess, a cup-shaped member arranged over the inner end of said core member within the recess, and said cup-shaped member being impermeable to gases. 5

5. A stopper for bottles adapted to contain gas-evolving liquids comprising, a stopper element having a cylindrical peripheral surface, said stopper element having a longitudinal recess therein, a relatively rigid core member arranged within said recess, and means impermeable to gases covering the inner end of said core member within said recess. 10
